UNITED STATES PATENT OFFICE.

ARTHUR F. RANDALL, OF BOSTON, MASSACHUSETTS.

LOUD SPEAKER.

Application filed September 7, 1926. Serial No. 133,953.

My invention relates to sound producing apparatus and particularly to electrically operated loud speakers such as are used for radio reception.

5 The main object of my invention is to provide an electrically operated loud speaker of simple and efficient construction which will operate with clarity, volume and accuracy of reproduction.

10 To these ends I have provided a loud speaker having the peculiar features of construction and mode of operation set forth in the following description, the several novel features of the invention being particularly 15 pointed out and defined in the claims at the close thereof.

In the accompanying drawings:

Figure 1 is a central vertical sectional view of a loud speaker constructed in accordance 20 with my invention.

Figure 2 is a front view of the instrument shown in Fig. 1.

Figure 3 is a rear view of a portion of the instrument shown in Fig. 1.

25 My new loud speaker, as herein shown, comprises a conical horn 1 which, as indicated in Fig. 1, is preferably made with a sixty degree taper, and to the smaller end of this horn is secured a phone unit 2, said unit 30 being wholly supported by the horn 1.

At or near its larger end the horn 1 is provided with an outwardly extending diaphragm flange 3 which is preferably of the conical shape shown, and whose annular wall 35 is preferably at right angles to the wall of the horn 1 as indicated in Fig. 1 of the drawings. That is, with the form of construction herein illustrated, the conical diaphragm flange 3 is approximately at right angles to the wall of the horn 1 and the two are disposed oppositely with relation to each other so that horn 1 occupies a position almost wholly within the conical flange 3. The angular 40 relationship referred to, however, may be varied and I have secured excellent results with the walls disposed at other angles than that described, but the best results in volume and clearness were secured with the particular relationship described.

45 The conical flange 3 is made with a marginal portion 4 that is flat and occupies a position between two rings 5 and 6 made from mill-board, wood or other suitable material, said rings being clamped together against opposite sides of said flat marginal portion by means of bolts 7.

The horn 1 is made with a metal terminal 1^a into the smaller end of which is frictionally fitted, or soldered, the nipple 8 of the metal housing 9 of the phone unit 2, the diaphragm 10 of the latter being thus disposed opposite, and close to, the rear smaller end of the horn 1.

When the speaker is operating the diaphragm 10 projects sound waves through the horn 1 which in turn vibrates the conical flange 3 so that the latter is thereby caused to project sound waves also. The result is a blending of the waves of the horn and flange but with the pitch apparently controlled by the flange. These sound waves are greatly amplified by the vibrations of the phone unit housing or frame 9 which are imposed upon the horn and transmitted by the latter to the flange 3. That is, both the vibrations of the diaphragm 10 and of the housing 9 are transmitted to horn 1 and flange 3 thus giving maximum volume. At the same time the reproduction is clear and free from distortion.

25 Two of the bolts 7 are utilized to fasten one of the leaves of a hinge 11 to the rear side of the ring 6, and the other leaf of this hinge is fastened to the upper end of a leg consisting of two sections 12 and 13 hinged together at 14. At its lower end the leg 12—13 30 is provided with a laterally extending foot 15 to hold the instrument against rolling sidewise. This leg serves as a prop to support the instrument in a substantially upright position.

35 The horn 1 with its flange 3 is preferably made from paper or the like.

What I claim is:

1. A sound producing instrument comprising a relatively large hollow conical member 95 of sheet material rigidly connected adjacent its middle with the larger end of a relatively small reversely disposed conical member of sheet material, and electromagnetic operating means rigidly connected with and wholly supported by said relatively small member, 100 said operating means including a direct acting armature diaphragm closing the smaller end of the relatively small member and an electromagnet rigidly fixed to said relatively 105 small member.

2. A sound producing instrument comprising two oppositely disposed hollow conical frustum members of different sizes whereof the larger end of the small member is connected with the smaller end of the large member; a direct acting sound producing 110

armature diaphragm connected with and closing the smaller end of the small member, and an electro-magnet rigidly connected with and wholly supported by the small member 5 for vibrating said diaphragm and said large member at sound frequencies.

3. A sound producing instrument comprising a horn of sheet material; a direct acting sound producing armature diaphragm 10 connected with and closing the smaller end of said horn; a direct acting conical sound producing diaphragm flange of sheet material rigidly connected adjacent its middle with the larger end of said horn and reversely 15 disposed so as to inclose the latter approximately throughout its length, and electrical- 20 frequencies.

4. A sound producing instrument comprising a hollow member of sheet material serving as conduit for sound waves; a direct acting conical sound producing diaphragm flange of sheet material rigidly connected adjacent 25 its middle with one end of said hollow member and reversely disposed to inclose the latter approximately throughout its length; a direct acting sound producing armature diaphragm connected with and closing the opposite end of said hollow member; electrically 30 operated means connected with and wholly supported by said hollow member for vibrating said closure diaphragm and said conical flange at sound frequencies, and means en- 35 gaging only the marginal portion of said conical flange for supporting said flange, said hollow member, said closure diaphragm and said electrically operated means.

ARTHUR F. RANDALL.
